CATTLE FEEDER

Mathew H. Stapleton, National Ave., Jefferson, Iowa

Filed July 6, 1962, Ser. No. 70,825

Term of patent 14 years

(Cl. D12—2)

FIG. 1

FIG. 2

FIG. 1 is a top plan view of a cattle feeder showing my new design; and

FIG. 2 is a front perspective view thereof.

The undisclosed side of the cattle feeder is substantially the same in appearance as the side shown in FIG. 2 except for the ladder.

I claim:

The ornamental design for a cattle feeder, substantially as shown and described.
